BATTERY TERMINAL PULLER

Filed Dec. 27, 1927

INVENTOR,
Henry E. Von Grimenstein,
By Minturn & Minturn,
Attorneys.

UNITED STATES PATENT OFFICE.

HENRY E. VON GRIMMENSTEIN, OF INDIANAPOLIS, INDIANA.

BATTERY-TERMINAL PULLER.

Application filed December 27, 1927. Serial No. 242,786.

This invention relates to means for removing terminals from the posts of batteries and has for its principal objects, an engagement of the terminals from their sides in cooperation with an upward pull on the terminals, whereby terminals that cannot be engaged from their under sides may be pulled from the posts without damage to the battery, the combination of such means in a small, simple 10 constructed unit having but one operating handle, and the provision of such a terminal puller at an exceedingly low cost of production. Other objects will be readily apparent in the following description of one particular 15 form of my invention, as illustrated in the accompanying drawing, in which—

Fig. 1, is a fragmentary front elevation of my terminal puller in an operative position over a battery;
 20 Fig. 2, a front elevation of the puller alone;
 Fig. 3, a side elevation;
 Fig. 4, a transverse section on the line 4—4 in Fig. 1; and
 Fig. 5, a transverse section on the line 5—5 25 in Fig. 1.

Like characters of reference indicate like parts throughout the several views of the drawing.

I form a bar 10 with bifurcated ends, in the 30 bifurcations of which are pivotally secured the two jaws 11 by the pins 12. I also form a second bar 13 with similarly bifurcated ends, into which the upper ends of the jaws 11 may 35 slidably enter and contact the rollers 14 rotatably carried therein.

The jaws 11 are each provided with a stop lug 15 which contacts against the lower bar 10 each within the respective bifurcations to 40 limit the outward swing of the upward ends of the jaws 11 whereby they are prevented from swinging entirely from out of the bifurcated ends of the upper bar 13.

A vertically positioned post 21 is screw-threadedly passed centrally through the top 45 bar 13, and slidably passed through the lower bar 10, and a handle 16 is secured in the upper end of the post as a means of turning the post 21.

The lower ends of the jaws 11 are inturned 50 each to have a sharpened tooth 17. The upper end of each jaw 11 has its inner edge shaped so that as the bar 13 travels upwardly away from the lower bar 10, the upper ends of the jaws 11 are forced apart by the rollers 14 to throw the teeth 17 toward each other. The extreme upper ends of the jaws are in-

turned by a curved portion to hook over the rollers 14 and limit the upward travel of the bar 13 thereby.

Referring to Fig. 1, it is usually found that 60 the terminal 18 is positioned on the battery post 19 so low that there is no opening or space between the terminal 18 and the top of the battery 20. Usually after long usage, the terminal 18 becomes corroded onto the post, 65 19. With my invention, the terminal 18 so corroded may be easily and quickly removed without injury to the battery itself.

To operate the puller, the post 21 is turned 70 to carry the bar 13 toward its lower end down against the bar 10, whereupon the upper ends of the jaws 11 may be swung inwardly (see dotted lines, Fig. 2) to throw the teeth 17 apart. In this position the puller is placed over the terminal 18 with the lower 75 end of the post 15 centrally positioned on the top of the battery post 19 and the teeth 17 held in contact against the outer side of the terminal 18.

The post 21 is then turned to cause the bar 80 13 to travel upwardly to press the upper ends of the jaws 11 outwardly to cause the teeth 17 to bite into the sides of the terminal 18 as in Fig. 1. At the same time the bar 13 is travelling upward to spread apart the upper 85 ends of the jaws 11, there is a vertical component lifting force applied to the teeth 17 tending to pull the terminal 18 upwardly off the battery post 19. If the terminal has not started to lift by the time the rollers 14 reach 90 the upper inturned ends of the jaws 11 or the lugs 15 have contacted the bar 10, the teeth 17 have already been set into the terminal sufficiently deep to withstand upward pull, and continued rotation of the post 21 95 will carry the bar 13 upwardly to bring the terminal 18 along therewith through the jaws 11, without causing the teeth 17 to bite deeper into the terminal 18. The terminal 18 is made of lead and the teeth 17 biting into it 100 causes no objectionable damage.

What I desire to secure by Letters Patent and claim as new is:

1. In a battery terminal puller, a pair of jaws, a lower bar pivotally securing the jaws in a spaced apart relation, an upper bar, a post screw-threadedly passed through the upper bar and adapted to slidably pass through the lower bar, said upper bar being associated with said jaws whereby upward 110 travel of said bar on said post will cause the lower ends of the jaws to swing toward each

other and stop means associated with the lower bar limiting the inward swing of the jaw ends.

2. In a battery terminal puller, a bar having slotted ends, a jaw pivotally secured within the slot of each end, each jaw having an inwardly projecting lug adapted to strike the bar upon the upper ends of the jaws swinging outwardly, a screw-threaded post 10 passed freely through the bar between said

jaws, an upper bar screw-threadedly engaged by the post, said upper bar having slotted ends to slidingly receive the upper ends of the jaws therethrough, and said jaws having their upper ends directed inwardly 15 whereby travel of the upper bar away from said first bar spreads apart said jaws.

In testimony whereof I affix my signature.

HENRY E. von GRIMMENSTEIN.
